UNITED STATES PATENT OFFICE.

ERNEST N. HUMPHREY, OF NEW BRITAIN, CONNECTICUT, ASSIGNOR TO THE TRAUT & HINE MANUFACTURING COMPANY, OF NEW BRITAIN, CONNECTICUT, A CORPORATION OF CONNECTICUT.

CUTTING DEVICE.

1,088,900.

Specification of Letters Patent.

Patented Mar. 3, 1914.

Application filed March 7, 1913. Serial No. 752,628.

To all whom it may concern:

Be it known that I, ERNEST N. HUMPHREY, a citizen of the United States, residing at New Britain, county of Hartford, 5 and State of Connecticut, have invented certain new and useful Improvements in Cutting Devices, of which the following is a full, clear, and exact description.

This invention relates to a cutting device 10 and particularly to that type known as cigar cutters and it is the object of the present invention to provide a thin flat device of this character of simple and inexpensive construction and efficient operation. The 15 structure of my invention lends itself readily to manufacture from stamped sheet metal and the cutting element is such that broken safety razor blades may be utilized for this purpose, so that taken altogether, 20 the device is one which may be very cheaply constructed without detracting from its efficiency. To this end I have provided the structure recited in the following detailed specification taken in connection with the 25 accompanying drawings illustrating a preferable embodiment of the invention.

In these drawings: Figure 1 is a view in front elevation of my cutting device with the parts in folded position and with the 30 blade holder shown in raised position in dotted lines. Fig. 2 is a view in elevation of the free end of the closed device shown in Fig. 1. Fig. 3 is a longitudinal sectional view partly in elevation. Fig. 4 is a top 35 plan view of the device shown in full lines in Fig. 1.

Referring to the drawings by numerals, 1 indicates the guard section of the device formed from sheet metal folded upon itself 40 to provide an elongated channeled body between the sides and within the channel of which the cutting edge of the blade may extend. This body is provided with an offset end 2, the base of this offset end being preferably cut out as at 3 to provide bifurcated 45 arms. The opposite end of the body 1 is of slightly greater width, as 1^a, the purpose of which will be hereinafter described.

Coöoperating with the guard section is a 50 blade holder section 5, likewise formed of sheet metal folded upon itself to form a complementary elongated channeled body within the channel of which the upper end of a cutting blade 7 of the wafer type is seated. The under edge of this blade holder

section conforms substantially in shape to the outline of the upper edge of the guard section. Blade holder section 5 is provided with a laterally offset end 6 which overlaps and extends in between the sides of the 60 bifurcated end 2 of the guard body 1 and is pivoted thereto by means of a tubular rivet 8. This end 6 at the point of its junction with the main body 5 of the guard section is preferably offset somewhat to 65 bring it in a plane centrally of the blade holding section and in line with the channel between the faces of the guard section, so that the faces of the guard and blade holding sections will lie in the same plane. 70

The guard section adjacent its free or non-pivoted end is provided with aligned apertures 4 therein through which the end of a cigar or other article may be inserted in order that it may be cut by the blade 7. The 75 extended portion 1^a at the free end of the guard member permits the blade 7 to be retracted from the guard section, sufficiently far to uncover the apertures 4 therethrough. In order, however, to retain the edge of the 80 blade within this guard section so that it will always be guided therein and will not be injured or distorted, I prefer to limit the relative movement between the blade holder and guard section and accomplish this by 85 providing the offset end 6 of the blade holding section with an arcuate slot 10 therein, taken with the tubular rivet 8 as a center, and in providing the guard section with a pin 9 extending through said slot and serving to limit the relative movement between the two sections of the device. The width of the blade is, of course, proportioned to the width of the guard section and to the length of the slot 10, so that its cutting edge 95 will be held from contact with the bottom of the channel guard member, and so that the adjacent edges of the blade holding and guard sections will abut and be in parallel relation when the parts are folded. 100

The device herein described affords an inexpensive and efficient cutting device for the purposes recited and for analogous uses and presents a neat appearance and a compact structure. Being flat, it may be very 105 conveniently carried in the pocket.

While I have herein described a specific embodiment of this invention, it will, of course, be understood that various structural changes are possible within the spirit 110

2
of the invention and the scope of the appended claims.

What I claim therefore and desire to secure by Letters Patent is:

5. 1. In a device of the character described, in combination, two pivotally interconnected and transversely alined parts, one of said parts comprising a flat sheet metal guard member of channel section having alined 10 apertures therethrough adjacent its non pivoted end, a complemental flat sheet metal blade holding member of channel section having a blade seated within the channel thereof with its cutting edge projecting 15 from its channel into the channel of said guard member, the end of one of said members being laterally offset and extending into the channel of the other and being pivotally mounted therein and said members 20 being provided with means positioning the cutting edge of said blade above the base of the channel of said guard member when said members are in fully closed position.
2. In a device of the character described, 25 in combination, two pivotally connected and transversely alined parts, one of said parts comprising a flat sheet metal guard member of channel section having alined apertures

therethrough adjacent one end and having its opposite end provided with a bifurcated portion, a complemental flat sheet metal blade-holding member of channel section having a lateral offset adjacent one end extending within and pivotally secured to the bifurcated portion of said guard member 35 and having a blade member seated within its channel portion with its cutting edge extending within the channel of said guard member, the adjacent edges of said guard and blade-holding members being of complemental contour whereby when said blade-holding member is positioned to bring the cutting edge of its blade below the lower edge of said alined apertures, said adjacent edges will lie in parallel relation and will 40 contact to position the cutting edge of said blade above the base of said channeled guard member, and means arranged to limit the withdrawal of the cutting edge of the blade member to a point adjacent the upper 50 edges of the alined apertures in the guard member.

ERNEST N. HUMPHREY.
